TELEPHONE STAND

Charles C. Bloomfield, Sr., Baton Rouge, La.

Application January 31, 1950, Serial No. 7,607

Term of patent 14 years

(Cl. D33—14)

To all whom it may concern:

Be it known that I, Charles C. Bloomfield, Sr., a citizen of the United States, residing at Baton Rouge, in the parish of East Baton Rouge and State of Louisiana, have invented a new, original, and ornamental Design for a Telephone Stand, of which the following is a specification, reference being had to the accompanying drawing, forming part thereof.

The figure is a perspective view of a telephone stand, showing my new design.

The stand is symmetrical and the left side has the same appearance as the right side.

I claim:

The ornamental design for a telephone stand, substantially as shown and described.

CHARLES C. BLOOMFIELD, SR.
